UNITED STATES PATENT OFFICE.

CARL HEINRICH FLORENZ MÜLLER, OF HAMBURG, GERMANY.

INCANDESCENT ELECTRIC LAMP.

SPECIFICATION forming part of Letters Patent No. 317,171, dated May 5, 1885.

Application filed June 14, 1884. (No model.) Patented in England October 2, 1882, No. 4,676.

To all whom it may concern:

Be it known that I, CARL HEINRICH FLORENZ MÜLLER, a subject of the Emperor of Germany, and a resident of Hamburg, in the German Empire, have invented certain new and useful Improvements in Incandescent Electric Lamps, of which the following is a specification.

My invention relates to improvements in electric lamps where the light is produced by the incandescence of a carbon filament in a vacuum; and the objects of my improvements are, first, to shape the carbon filament in such a manner that around the axis of the lamp or bulb an equal lighting-surface will be visible; and, second, to facilitate the connection of the carbon filament with the glass bulb. I attain these objects by the device illustrated in the accompanying drawings, in which—

Figures 1 and 2 are side elevations of my improved electric lamp from two different points of view, situated at right angle to each other. Fig. 3 is a top view.

Similar letters refer to similar parts throughout the several views.

The carbon filaments of incandescent lamps as used up to this day allow only a single line or little more to be visible when observed from certain points of view, as the ascending part of the bow obscures the descending one, and vice versa. The diffusion of the light at such points of view is proportionately smaller than at such points where the complete bow can be seen, as the quantity of the diffused light decreases with the decreasing lighting-surface.

It has been proposed to make the carbon filament in the form of two spirals crossing each other, in order that the filament can expand and contract freely; but the spirals have been of a very compact form, consequently each spiral obstructs a considerable portion of the light emitted by the other.

According to my invention the carbon filament *a* is shaped in such a manner as to form two open cylindrical or conical spirals crossing one another, which terminate in a bow, *a'*, common to both, the diameter of said bow being the same or nearly the same as that of

the spirals. The two spirals and the terminal bow are made of a single filament bent in the manner shown, or of two filaments united at one of their ends, and the free ends are connected to the platinum wires *b* in any convenient manner. The conducting-wires *b* are sealed into glass tubes *c*, which, at their upper extremities, are bent outward and pass through the side walls of the small protuberance *e'*, formed on the bulb *e* at points diametrically opposite to each other. The glass tubes *c* are connected together and braced by means of the glass bars *d*. The bulb is sealed at the point *f* on the summit of the bulb in the usual way after a sufficient vacuum has been produced within the bulb. This arrangement of the point *f* causes the light of the lamps to be diffused more equally from the incandescent carbon, as no projection, &c., will interrupt the globe or otherwise shaped surface of the glass bulb.

Having thus fully described my invention, what I desire to claim, and secure by Letters Patent, is—

1. In an incandescent lamp, a carbon filament in the shape of an open double spiral, the windings of which extend in an inclined horizontal direction and cross each other, so that the filament presents an equal amount of lighting-surface on all sides, substantially as 75 and for the purpose set forth.

2. In an incandescent electric lamp, a carbon filament, *a*, of the shape of an open double spiral, the windings of which extend in an inclined horizontal direction and cross each other, terminating in a bow, *a'*, the filament thus formed presenting an equal amount of lighting-surface from all sides, substantially as 85 and for the purpose set forth.

3. The combination, in an incandescent 90 electric lamp, of the bulb *e*, having the protuberance *e'*, with the connecting-wires *b*, incased in the glass tubes *c*, the outer ends of which pass through the walls of the bulb at points diametrically opposite to each other, together with the bars *d* and the carbon filament *a*, substantially as and for the purpose set forth.

4. The combination, in an incandescent 95 electric lamp, of the bulb *e*, connecting-wires 100

b, tubes *c*, and bars *d*, with the carbon filament *a*, of the shape of an open double spiral, the windings of which cross one another, terminating in a bow, *a'*, substantially as and for the purpose set forth.

In testimony that I claim the foregoing as my invention I have signed my name, in pres-

ence of two witnesses, this 17th day of May, 1884.

CARL HEINRICH FLORENZ MÜLLER.
